DETACHABLE SOLE AND HEEL

Ernest Myers Dignan, London, England, assignor
of one-half to Percival Glen Lawson-Johnston,
London, England

Application August 9, 1933, Serial No. 684,310
In Great Britain March 3, 1932

5 Claims. (Cl. 36—36)

This invention relates to soles and heels for boots and shoes and has for its object to enable a worn sole or heel very easily and cheaply to be replaced without skilled labour.

5 To this end and in accordance with this invention the improved sole or heel comprises a frame; the external outline of which is shaped suitably, which is formed with an aperture or apertures at or about its central part, the margin of each 10 such aperture being notched to receive the necks of studs or pads of India rubber or the like, and which is formed at that face which is to be contiguous with the sole or heel of the boot or shoe with a distance piece constituted by a marginal 15 rib or by undercutting the edges of the notches, whilst a plate is adapted to be secured in or over each aperture, so as to retain in position the studs or pads, the flanged inner ends of which lie within the space afforded by the distance piece 20 on the frame.

The pads to be secured in this manner may be formed with outer heads so shaped that when assembled in position they constitute together a complete or substantially complete sole or heel.

25 In some cases, however, e. g. where separated studs are desired the margin of the plate may be notched, its notches being complementary to those in said frame, and the plate fitting as closely as possible the aperture in the frame, alternatively, 30 the plate may be so shaped that the tongues lying between the notches are adapted to extend over the corresponding parts of the frame.

The frame may be made of metal, hard India rubber, leather or other suitable material and 35 may be secured to the sole or heel of a boot or shoe by screws or the like. After the frame has been so secured, the pads or studs are slid into position in the respective notches, their flanged inner ends lying in the space afforded by the distance piece on said frame, after which the plate is 40 applied and secured by a central screw. In the event of wear, the plate is removed, any worn pad or stud is removed and a new one substituted, after which the plate is replaced—an operation 45 for which no skilled labour is required.

If the assemblage of studs is to constitute a complete or substantially complete sole or heel, the plate may be constituted by a mere disc of similar material which fills up the central space 50 which must be left to permit the sliding of the necks of the pads into and out of the respective notches. Similarly where separated studs are desired, the plate may be arranged completely to fill the residual space but without projecting so far 55 as the outer ends of the studs or it may be a metal

plate adapted to overlap the frame between the studs i. e. a mere cover plate, parts of the margin of which are notched to coact with the studs to hold them in position and at the same time exclude dirt from the space within the frame.

The inner ends of the studs or pads may be flanged or they may be formed with dovetailed 10 projections, the notches in the frame being formed correspondingly and in cases where the pads constitute substantially the complete sole or heel, the plate may be bevelled or rabbetted at its edges partly to overlie the contiguous edges of the pads.

In the accompanying drawing Figure 1 is an inverted plan of one form of boot heel made in 15 accordance with this invention, part being broken away for the sake of clearness. Figure 2 is a fragmentary section as on the line 2—2 Figure 1, Figure 3 is a fragmentary section of a modified detail, Figure 4 is an inverted plan of a modified 20 form of boot heel with one stud omitted; Figure 5 is a fragmentary section on the line 5—5 Figure 4, whilst Figure 6 is a fragmentary section of a detail.

As shown in Figures 1 and 2 a suitably shaped 25 plate *a* is secured to the main body *b* of a boot heel by means of screws such as *c*, said plate *a* being apertured centrally and formed with slots *d* . . . undercut as at *e* . . . into each slot *d* is slid the neck *f* of a pad *g* a flanged part *h* on 30 said neck passing into the undercut part *e*. The pads *g* . . . together constitute the greater part of the surface of the heel and after they have been slid into position a central plate or pad *j* completes the surface and prevents movement 35 of the pads *g* . . . ; the pad *j* is secured by a central screw *k*.

Figure 3 illustrates a modification in which the pad *g* is formed with a dovetailed projection *m* instead of a neck *f* and flanged part *h*, the projection *m* meshing with a dovetail *s*.

Figures 4 and 5 show a further modification in which the pads *g* . . . are replaced by studs *n* . . . and the pad *j* by a notched plate *o* the notches of which are complementary to those of the plate *a*.

In some cases the pad *j* may be bevelled or rabbetted at its edge partly to overlie the contiguous edges of the pads *g* . . . whilst, if desired, the edges of the plate *o* between its notches may overlie the corresponding parts of the plate *a*.

Figure 6 shows how a plate *p* having a hooked end *q* may be arranged to slide in the main body *b* to engage a perforated lug *r* on the pad *j* to retain the latter in position, the pad *j* having a dovetailed projection *m'* which is similar to the pro-

jection *m* (Fig. 3) and which meshes with a dovetail *s'* similar to the dovetail *s*.

I claim:—

1. A wearing surface for a sole or heel, comprising a frame adapted to be secured thereto and formed with a distance piece, said frame having a substantially central aperture, the edge of said aperture being formed with notches, pads flanged at their inner ends and having necks adapted to 10 be received by said notches, the flanged inner ends of said pads lying within the space afforded by said distance piece, and a plate registering substantially with said aperture and adapted to be secured to a sole or heel and to maintain said 15 pads in position.
2. A wearing surface for a sole or heel, comprising a frame adapted to be secured thereto and formed with a distance piece, said frame having a substantially central aperture, the edge of 20 said aperture being formed with notches, pads flanged at their inner ends and having necks adapted to be received by said notches, the flanged inner ends of said pads lying within the space afforded by said distance piece, and a plate registering substantially 25 with said aperture and adapted to be secured to a sole or heel and to maintain said pads in position.

3. A wearing surface for a sole or heel as claimed in claim 1 wherein the edge of the plate is formed with notches complementary to those in the frame.

4. A wearing surface for a sole or heel, comprising a frame adapted to be secured thereto and formed with a distance piece constituted by a marginal rib, said frame having a substantially central aperture, the edge of said aperture being formed with notches, pads flanged at their inner 10 ends and having necks adapted to be received by said notches, the flanged inner ends of said pads lying within the space afforded by said distance piece, and a plate registering substantially 15 with said aperture and adapted to be secured to a sole or heel and to maintain said pads in position.

5. A wearing surface for a sole or heel, comprising a frame adapted to be secured thereto and having a substantially central aperture, the edge 20 of said aperture being formed with undercut notches, pads flanged at their inner ends and having necks adapted to be received by said notches, the flanged inner ends of said pads being received in the undercut parts of said notches, 25 and a plate registering substantially with said aperture and adapted to be secured to a sole or heel and to maintain said pads in position.

ERNEST MYERS DIGNAN.
